MANUFACTURE OF COVERED TUBING

Karl Pape, Dover, N. J., assignor to Resistoflex Corporation, Belleville, N. J., a corporation of New York

Original application April 27, 1940, Serial No. 331,952. Divided and this application April 24, 1941, Serial No. 390,037

4 Claims. (Cl. 91--18)

This invention relates to the manufacture of linear articles which have a woven or braided covering.

More particularly, the invention pertains to apparatus for use in the step of bonding such covering to the underlying material by the application of solvent or solvent vapor.

This application is a division of my co-pending application Serial No. 331,952, filed April 27, 1940, wherein there is described a method of covering tubing of synthetic plastic material with a woven or braided fabric. The apparatus herein described and claimed may be used in carrying out the covering of tubing but its use is not limited thereto as it may be used in bonding fabric covering to other linear articles such as insulated wire or the like.

As is well known, linear articles, such as flexible tubing, may have a fabric covering formed directly thereon in various types of braiding machines or looms for weaving tubular fabric.

It is to be understood that the term "weaving" as used hereinafter or in the claims is intended to include braiding as a particular type of weaving, and the reference to "fabric" or "textile fabric" includes not only coverings formed of the various types of fibrous yarns but also coverings formed of wires or other filaments.

It is the principal object of the present invention to provide means by which a uniform bonding of the fabric cover to the underlying material may be effected and to that end to automatically stop the application of solvent upon stopping of the machine by which the covering is being formed.

Other objects and advantages will appear in the course of the following description.

As an illustration of how the invention may be practiced, the present preferred embodiment thereof will now be described. In describing this embodiment the covering of tubing of a flexible and elastic polyvinyl alcohol composition will be used as an example. This plastic material is more or less soluble in water and capable of being softened slightly and rendered adhesive on its surface when subjected to steam for only a short time.

The covering of this tubing may be accomplished in a braiding machine of well-known construction, preferably with certain modifications such as those described in my aforesaid co-pending application. The apparatus of the present invention may be used and operated in combination with the mechanism of such a braiding machine, as will be readily understood from

the following description, taken in connection with the drawing in which:

Fig. 1 shows certain essential parts of a braiding machine with the addition of a solvent applying device for use in accordance with the invention;

Fig. 2 shows the means for controlling the application of solvent to the tubing and its relationship to the braiding machine, part of which is shown somewhat schematically;

Fig. 3 shows, in greater detail, the automatic air control and the means for actuating it upon stopping of the braiding machine;

Fig. 4 is a vertical longitudinal section through the solvent applying chamber;

Fig. 5 is a section of the same on the line 5x—5x of Fig. 4; and

Fig. 6 is a cross-section on the line 6x—6x of Fig. 4.

Referring to the drawing, Fig. 1 shows certain parts of a common type of braiding machine including a slotted plate 11, the slots in which determine the travel of carriers 12 which are actuated in the usual manner by a gear train (not shown). Each carrier holds the usual cylindrical cross-wound spool 13 and is provided with the usual yarn tensioning device 16. The plate 11 has a central aperture 18 through which passes the tubing 20 which is to be covered. (After being covered, the tubing is designated 20'). The tubing is usually unwound from a reel (not shown) underneath the machine. As is well known the carriers, which may vary in number but of which there are usually at least 24, travel about the tubing in such manner as to weave a braid thereon. The tubing passes upwardly over a rotating capstan 21. To hold the tubing in contact with the capstan, a spring-actuated roller 28 is usually provided and is pressed against the capstan by any suitable means. As the tubing 20 passes off the capstan 21, it is directed through the solvent applying device 29.

If it is desired to maintain the tubing 20—20' under an inflating pressure during the braiding process, a short length of flexible tubing 30 may be provided with a fitting 31 which can be inserted into the end of the tubing 20'. The tubing 30 is connected with a compressed air line 32 which may be equipped with pressure gauge 34. The other end of the tubing 30 may be made airtight by folding it over and clamping it, as shown at 33.

The chamber 29 in which the solvent is applied for bonding the covering to the tubing as it leaves the capstan is shown in detail in Figs. 4, 5 and 6,

and is constructed as follows: The chamber proper is a sheet metal cylinder, the ends of which are closed except for openings in the upper part through which the tubing 20' passes. These openings are preferably in the form of short tubes 60, 61, the edges of which are turned inwardly to closely fit the tubing 20'. The tubes 60, 61 are provided with openings 62, 63 within the chamber 29 through which any condensate can drain into the chamber. A pipe 64 having a central opening 65 passes through the chamber from one side to the other and is secured therein by soldering or the like, so that the opening of the pipe is directed away from the tubing 20, thus preventing the steam, which is the solvent vapor used in this embodiment, from blowing directly against the tubing. The pipe 64 is connected at one end to a steam line 66 in which is interposed a manually operated valve 67 having a hand wheel 68 which is extended to a position convenient for the operator of the braiding machine. The other end of the pipe 64 is connected to a compressed air line 69 containing a check valve 70 which permits air to enter the chamber 29 but prevents steam or condensate from entering the air line. At the lowermost portion of the chamber 29, as it is normally positioned as shown in Fig. 1, it opens into a drain pipe 71.

In order to obtain the correct amount of steam, the valve 67 is opened until the steam can be seen emerging from the tubing 60 or 61 and it is then shut down to the point where there is just enough steam escaping to be visible.

Braiding machines are customarily provided with means for automatically stopping the machine whenever a yarn breaks or a spool becomes empty. If the application of solvent were allowed to continue during the periods when the braiding machine is stationary, some sections of the tubing 20' would be subjected to the effects of the solvent for longer periods than others, which would be liable to damage the tubing and would produce a non-uniform product. The present invention provides means for automatically scavenging the steam or other solvent from the chamber 29 immediately upon the stoppage of the machine. As shown in Figs. 2 and 3, the air line 69 is controlled by a plunger type air valve 80 which is actuated by a plunger 81. This valve is mounted adjacent the standard trip device 82 which is pivotally mounted on the plate 11 of the braiding machine adjacent the slots 84 in which the carriers 12 travel.

As is well known, when a yarn breaks or a spool becomes empty, a shoe 85 on the carrier 12 (Fig. 1) drops to the bottom of the carrier and engages the trip lever 82, the path of the shoe 85 being indicated in dotted lines in Fig. 3. This moves the lever 82 to the right, as shown in the drawing, and disengages a clutch (not shown) through the medium of an upwardly extending stud 86. The lever 82 at the same time presses against the plunger 81 and admits air into the air line 69, the manually operated air valve 90 being open at this time. The lever 82 remains in this position, holding the air valve 80 open, until the machine is started again by moving lever 82 to the left. Immediately on stopping of the machine, however, the operator closes the steam valve 67 and thereafter closes the manual air valve 90. When the machine is again started, the steam valve 67 is opened and adjusted and, the plunger air valve 80 then being closed, the manual air valve 90 is re-opened. The machine is then in condition automatically to blow air

5 into the chamber 29 when it stops again. If the operator stops the machine, he does so by moving lever 82 to the right and the air valve 80 is opened in the same manner as when the machine stops itself automatically.

The injection of air into this chamber 29 through pipe 69 (see Fig. 6) has the effect of condensing the steam, the condensate draining out through pipe 71. The air also blows out around the tubing 20' through the tubes 60 and 61, thus bathing the tubing in a stream of air instead of solvent vapor.

The foregoing detailed description is to be considered as merely illustrative as various modifications may be made within the purview of the invention as defined in the claims.

What is claimed is:

1. Apparatus for bonding a woven covering to a linear article by the application of a solvent to said article through said covering as it leaves the machine by which said covering is applied, said machine being provided with stopping mechanism including a part which is moved in one direction upon stopping and in the opposite direction upon starting said machine, said apparatus comprising a chamber through which said article passes after being covered, a conduit adapted to introduce solvent for the article into said chamber, an air line adapted to introduce compressed air into said chamber, and a valve in said air line operatively associated with said part so as automatically to be opened upon the movement of said part when the machine stops and closed upon the opposite movement of said part when the machine starts.

2. Apparatus for bonding a woven covering to a linear article by the application of a solvent to said article through said covering as it leaves the machine by which said covering is applied, said machine being provided with stopping mechanism including a part which is moved in one direction upon stopping and in the opposite direction upon starting said machine, said apparatus comprising a chamber through which said article passes after being covered, a conduit adapted to introduce solvent for the article into said chamber, a manually operated valve in said conduit, an air line adapted to introduce compressed air into said chamber, and a valve in said air line operatively associated with said part so as automatically to be opened upon the movement of said part when the machine stops and closed upon the opposite movement of said part when the machine starts.

3. Apparatus for bonding a woven covering to a linear article by the application of a solvent to said article through said covering as it leaves the machine by which said covering is applied, said machine being provided with stopping mechanism including a part which is moved in one direction upon stopping and in the opposite direction upon starting said machine, said apparatus comprising a chamber through which said article passes after being covered, a conduit adapted to introduce solvent for the article into said chamber, a manually operated valve in said conduit, an air line adapted to introduce compressed air into said chamber, and a valve in said air line operatively associated with said part so as automatically to be opened upon the movement of said part when the machine stops and closed upon the opposite movement of said part when the machine starts, and a second manually operated valve in said air line.

4. Apparatus for bonding a woven covering to

a linear article by the application of a solvent to said article through said covering as it leaves the machine by which said covering is applied, said machine being provided with stopping mechanism including a part which is moved in one direction upon stopping and in the opposite direction upon starting said machine, said apparatus comprising a chamber through which said article passes after being covered, a pipe extending through said chamber and having an opening 10 within the chamber directed away from the path

of said article, a conduit connected to one end of said pipe for conveying solvent thereto, an air line connected to the other end of said pipe for conveying compressed air thereto, and a valve in 5 said air line operatively associated with said part so as automatically to be opened upon the movement of said part when the machine stops and closed upon the opposite movement of said part when the machine starts.
